ELECTROSURGICAL INSTRUMENT

Filed April 26, 1939

UNITED STATES PATENT OFFICE

2,275,167

ELECTROSURGICAL INSTRUMENT

William Bierman, New York, N. Y.

Application April 26, 1939, Serial No. 270,175

9 Claims. (Cl. 123—303.17)

This application relates to surgical devices. More particularly, my invention relates to an improved construction for electro-surgical instruments adapted for the removal of human tissue by means of an electrical current.

One of the objects of my invention is to provide an electro-surgical instrument of the character described which shall be so designed that new growths or diseased tissue in the human body may be removed with such accuracy that only the desired portion is destroyed while the adjacent healthy tissue is left completely intact.

Another object of my invention is to provide an electro-surgical instrument of the character described in which the volume of the tissue to be destroyed at one time is precisely limited to a predetermined amount.

Still another object of my invention is to provide an electro-surgical instrument of the character described having means for forcing the tissue to assume a polypoid shape, i. e., one in which there is a narrow constricted stem region and an enlarged region above the constricted stem region to facilitate the tissue destruction.

A still further object of my invention is to provide an electro-surgical instrument of the character described which shall comprise relatively few and simple parts, which shall be easy to assemble and relatively inexpensive to manufacture and which, at the same time, shall operate with a high degree of efficiency.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the claims.

In the accompanying drawing, in which is shown one of the various possible embodiments of this invention,

Fig. 1 is a cross-sectional view of an electro-surgical instrument constructed in accordance with my invention;

Fig. 2 is an enlarged sectional view of a portion of the device shown in Fig. 1.

Fig. 3 is a cross-sectional view taken substantially on the line 3—3 of Fig. 2;

Fig. 4 is a view similar to Fig. 2 but showing a modified form of my invention;

Fig. 5 is a wiring diagram showing the use of an indicating light in connection with my invention; and

Fig. 6 is a cross-sectional view taken substantially on the line 6—6 of Fig. 1.

As is well known, the surgical technique employed for the removal of human tissue such as, for example, tonsillar tissue, consists in the use of high frequency currents which are applied by means of needle electrodes to the tissue to be removed. This technique is known as electro-surgery and its use is recognized by the medical profession as having definite advantages over the prior surgical techniques which involved cutting with sharp-edged instruments.

In the type of electro-surgical devices heretofore employed, certain inherent disadvantages were apparent. One such disadvantage was to be found in the fact that it was extremely difficult to localize the destructive action of the electric current. This was due to the fact that when the needle electrodes were applied to the tissue to be destroyed, any slight movement of the patient would tend to displace the electrode with the result that adjacent healthy tissue was also destroyed or harmed. Another disadvantage was found in the fact that it was difficult to determine in advance just how much of the tissue would be destroyed at one time.

Referring now in detail to the drawing, there is disclosed an electro-surgical instrument constructed in accordance with my invention and designed to overcome the above described disadvantages and at the same time to possess additional advantages whereby to provide an instrument of high efficiency. The electro-surgical instrument of my invention comprises an elongated main stem 10 being of hollow construction for the major portion thereof with the exception of the portion 10a adjacent one end thereof which is of substantially solid construction. Rotatably mounted on a portion of the main stem 10 adjacent the opposite end thereof from the end 10a is a hollow bushing 11 having an interior chamber 12 communicating with the interior of the main stem 10 by means of an aperture 14 in the wall of said main stem. The bushing 11 is prevented from lateral displacement by means of a collar 15 which may be integral with the stem 10, and a collared plug 16 threadedly received in the open end of the stem 10 and abutting the bushing 11 as shown. The bushing 11 is open at the bottom end thereof. A portion of the outer wall of said bushing 11 adjacent said open end is threaded and is adapted to have threadedly attached thereto a housing 18 containing a chamber 19 communicating with the chamber 12 of the bushing 11. The bushing 11 and

the housing 18 are preferably made of electrically insulating material such as, for example, Bakelite or the like. Threadedly attached to the housing 18 is a stem 20 which may also be of Bakelite and which is provided with a longitudinal through opening 21. The housing 18 and stem 20 serve as a handle for gripping the instrument. Attached to the bottom end of the stem 20 is a flexible tubing 22 in which the opening 23 therein communicates with the opening 21. An aperture 24 is provided in the housing 18 which communicates at one end thereof with the stem opening 21 and at the other end thereof with the chamber 19. The solid portion 10a of the stem is provided with a longitudinal aperture 25 which communicates at one end thereof with the hollow opening of the main stem and at the other end thereof with the surrounding atmosphere through the open end 10b of the stem. The stem or nozzle 20 is adapted to be connected to any suitable source of suction supply (not shown), by any suitable means such as, for example, the flexible tubing 22.

It is thus seen from the above described construction that when the suction device is rendered effective, air will be drawn from the open end 10b of the stem 10 through the aperture 25, the hollow tubular portion of the stem, the aperture 14, the chambers 12 and 19, the aperture 24 and the openings 21 and 23. A pair of washers 13 are interposed between the bushing 11 and the collar 15 at one side and between the bushing 11 and the plug 16 on the other side to prevent air leakage.

At the free end of the main stem there is provided a suction cup 27 which is formed by providing a sleeve 28 having the inner wall thereof threaded and adapted to be threadedly received on the externally threaded portion 29 of the solid stem portion 10a. By rotating the sleeve 28, it is possible to adjust the depth of the suction cup 27, the purpose of which will be explained as the description proceeds.

Mounted within the main stem is a central electrode 30 having one end 30a thereof connected to a source of current supply in the manner to be described, the other electrode end 30b being permanently held in position within an opening in the solid stem portion 10a. A portion 31 of the electrode 30 adjacent the end 30b is externally threaded as shown. Threadedly received on this portion 31 is a central electrode tip 32. This electrode tip 32 (the active electrode) is designed to contactively engage the tissue to be destroyed and may be adjustably moved in axial direction by merely rotating the same. The electric circuit may be completed as follows: A wire 35 is connected to one terminal of the current source and is in electrical continuity with the central electrode 30 in a manner to be subsequently described, and terminates as the central electrode tip 32 which, when in contact with tissue to be coagulated, serves as the active electrode. The larger dispersive electrode which is generally applied to any other suitable part of the body is connected to the other terminal of the current source. An alternative circuit may be employed wherein the active electrode remains as above described but in which the return supply is effected by grounding through the means of a metal collar 36 disposed adjacent the open end 10b of the stem and attached to a wire 35 which is grounded.

A still further alternative circuit which may be employed is to use the active electrode as described above but to effect the return supply

through the metal collar 36 attached to the wire 35 and thence connected to the other terminal of the current source instead of being grounded.

It is thus seen that when the open end 10b of the stem 10 is disposed at the point where it is desired to remove the tissue and the current is rendered effective through any of the above described means, the circuit will be completed by the tissue and the current will effect the destruction of said tissue.

As hereinbefore explained, it is of extreme importance that the only tissue destroyed shall be the diseased tissue which it is desired to destroy and, therefore, once the instrument has been properly located with respect to the tissue to be destroyed, if the source of suction is rendered effective, the said tissue will be drawn into the suction cup 27 and will thus be held in gripped position with respect to the electrode so that when the current is applied, only that tissue which it is desired to be destroyed will be destroyed and adjacent healthy tissue will not be harmed.

An exact delimitation of the area of tissue being destroyed is caused by the employment of the suction cup 27 around the electrode tip 32, since the pressure exerted on the tissue by the edge of the cup greatly restricts and substantially stops the flow of blood to and from the area to be destroyed without affecting blood circulation in the surrounding area not then to be destroyed. This abrupt change in blood circulation causes the region which is destroyed by heat due to coagulation by a high frequency current to be definitely limited, since tissue with an active circulation loses heat much more rapidly than tissue in which the circulation of blood has been substantially cut off.

When the suction cup 27 is applied to a pedunculated growth, said growth will be gripped and may be held with its body away from the tissue to which it is attached to maintain pedunculation and consequent freedom from contact with adjacent tissue during the period in which the high frequency current is applied. By this technique the coagulation occurs in the stem of the pedunculated growth, although said stem is spaced from the immediate region which the electrode touches. The destructive action of the current is thus automatically limited to the region where the pedunculated growth is smallest, i. e. at its base where pedicle or stem joins the supporting surface. Hitherto where no suction means had been used in conjunction with a coagulating electrode, it had been necessary to press the electrode against the surface to be destroyed and when this technique was practiced upon pedunculated growths such growths would be transformed into sessile shapes because of their intimate contact with the tissue from which they arose before coagulation and thus the advantage of coagulating the said growth at its stem would be lost.

It is also noted from the above described construction that the amount of tissue to be destroyed at one time may be precisely regulated by the relative distance between the open ends of the sleeve 28 and the end of the solid stem portion 10a. A nut 37 is provided which is threadedly received on the stem portion 10a for locking the sleeve 28 in any desired position.

In accordance with my invention, I have so designed the instrument that the electric current will not be rendered effective until the suction means has first been rendered effective to draw

the tissue within the suction cup 27. By such construction I am able to avoid the possibility of coagulating any tissue which it is not desired to destroy. The means by which this is accomplished will now be described. A poppet valve 40 is provided which serves as a closure for the chamber 12. The poppet valve 40 is attached to a stem 41 by any suitable attaching means such as the nuts 42. A portion of the stem is slidably received in an opening 43 in the housing 18, the said opening 43 communicating with an enlarged opening 44 which, in turn, communicates with the opening 21 of the nozzle 20. The poppet valve 40 is normally kept in closed position by means of a coil compression spring 45. The stem 41 is of electrically conductive material and is interconnected to the central electrode 30 by means of a conductor wire 46 passing through the aperture 14 in the wall of the stem 10. At the lower end of the housing 18 and disposed in the path of movement of the stem 41 is a thin flat spring 48 of electrically conductive material which is attachedly held in such position by means of a screw 49 passing through the spring 48 and contactively engaging a metallic sleeve embedded in the material of the housing 18, the said screw 49 and sleeve being also of electrically conductive material. A conductor wire 50 leading to the source of current supply has one bared end 50a thereof frictionally received in an electrically conductive sleeve embedded in the housing 18 and designed to contactively engage the first named sleeve holding the screw 49. It is thus seen that when the stem 41 is caused to slidably move downwardly against the action of the spring 45, the free end of the stem 41 contactively engages the spring 48 to complete an electric circuit between the central electrode 30 and the conductor wire 50 through the spring 48 and screw 49. The only manner in which the stem 41 may be caused to move downwardly to make the circuit just described is by rendering the suction means through the flexible tube 22 effective. This will cause the poppet valve to open in the manner hereinbefore described.

The valve 40 will open and remain open for a short time to complete the electric circuit which energizes the electrode 32. It will be noted that in order to practice my invention the valve 40 need not be maintained open for more than a few seconds as within this period coagulation is fully completed.

It is thus seen from the above described construction that the current cannot be rendered effective until the suction means has first been rendered effective, thereby preventing the coagulating of any tissue until the same has been drawn into the suction cup 27. A tubular member 55 is provided having one end 55a thereof opening to the surrounding atmosphere and the other end thereof communicating with the opening 21 in the nozzle 20. Said member 55 may be forced into the bore provided in the stem 20 after the latter has been screwed upon the housing 18. Also, if desired, the tube 55 may be cut off flush with the stem 20. By means of this tubular member 55, it is possible to start the vacuum pump in operation without causing the downward movement of the stem 41 and consequently without rendering the electric circuit effective. In operating the instrument, the vacuum pump may first be started in operation, which will draw air from the surrounding atmos-

phere through the tubular member 55 and down through the openings 21 and 23. When the instrument is properly positioned with respect to the tissue to be destroyed, the end 55a of the tubular member 55 exposed to the surrounding atmosphere may be covered in any suitable manner such as, for example, by placing a finger of the operator thereover in which case the air will be drawn from the chamber 19 through the opening 24 to cause the poppet valve 40 to withdraw from its normal closed position and at the same time to supply suction to the suction cup 27 to draw the tissue therein. Simultaneously with the above operation, the circuit of the electric current is rendered effective to destroy the tissue within the suction cup through contacting of the stem 41 and member 48.

While in the drawing I have illustrated a method of suction control by means of the finger, it is understood that a similar control may be employed for operation by foot.

The portion of the stem 10 adjacent the suction cup end may be angularly bent in any desired manner so that areas of tissue difficult of access may be reached with facility. Also the rotatable mounting of the bushing 11 and the attached nozzle 20 facilitates this action.

Means are provided to limit the amount of relative rotational movement between the bushing 11 with the nozzle 20 and the stem 10 to prevent strain and possible breaking of the wires 35 or 46 due to twisting. As shown in Fig. 6 of the drawing, the collar 15 is provided with a projecting lug 15a which is adapted to abut a pin 16b fixed to the bushing 11 after a predetermined amount of relative rotation.

The shape of the suction cup may take any desirable form such as, for example, that shown in Figs. 1 and 2 or, if desired, the suction cup 27' 40 may be pear-shaped as shown in Fig. 4 of the drawing. In this shape of suction cup, when the tissue is drawn up into the space within the cup, it takes the form of a pedunculated mass, i. e., a mass having an enlarged portion attached to a constricted portion or stem. When the current is applied at the expanded end through the electrode tip 32, the generated current becomes concentrated at the constricted end, thereby causing coagulation of only a very small area relative to the amount of tissue removed. By such construction of the suction cup, the possibility of primary or reactionary hemorrhage is minimized and for the same reason, the resulting scar tissue is relatively small.

In accordance with my invention the stem 10 may be constructed of a material which will possess sufficient resilience so as to permit of manually reforming the shape thereof to more readily gain access to otherwise inaccessible parts.

It is also noted that the active electrode tip 32 may be of any other desired shape from that shown, such as, for example, one having a sharp needle point.

If desired, in connection with my electro-surgical instrument, a pilot or indicating light 60 may be provided which may be connected as shown in Fig. 5 of the drawing. The pilot light 60 will thus be rendered effective when the circuit is closed by means of the stem 41, to dim the light 60.

It is to be noted that my invention may be satisfactorily practiced with a high frequency current using a biterminal or uniterminal technique. The metal collar may either be connected

to the ground which will further assist in exact delimitation of tissue to be destroyed, or the metal collar itself may be connected directly to the other terminal of the current source.

It will thus be seen that there is provided a device in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawing is to be interpreted as illustrative and not in a limiting sense.

Having thus described my invention, I claim as new and desire to secure by Letters Patent:

1. An electro-surgical instrument for removing human tissue, comprising a hollow stem of insulating material open at one end and adapted to be connected to a vacuum device for creating a suction at said open end to draw in and hold said tissue, said open end being adapted to be stoppered by said drawn-in tissue, an electrode in said stem having a portion thereof disposed adjacent said open end so as to intimately contact said drawn-in tissue, means for connecting said electrode to a source of current supply, and means for preventing the energization of said electrode without first rendering said vacuum device effective for drawing in said tissue.

2. An electro-surgical instrument for removing human tissue, comprising a hollow stem of insulating material open at one end and adapted to be connected to a vacuum device for creating a suction at said open end to draw in and hold said tissue, said open end being adapted to be stoppered by said drawn-in tissue, an electrode in said stem having a portion thereof disposed adjacent said open end so as to intimately contact said drawn-in tissue, means for connecting said electrode to a source of current supply, and means for normally rendering ineffective the suction action for drawing in said tissue while said vacuum device is in operation.

3. An electro-surgical instrument for removing human tissue, comprising a hollow stem of insulating material open at one end and adapted to be connected to a vacuum device for creating a suction at said open end to draw in and hold said tissue, an electrode in said stem having a portion thereof disposed adjacent said open end so as to intimately contact said drawn-in tissue, means for connecting said electrode to a source of current supply, and means for limiting the amount of tissue to be suctionally drawn into said open end, said last named means comprising a sleeve mounted on said stem adjacent the open end thereof, said sleeve being movable axially to project beyond the said open end of said stem to form a suction cup area.

4. An electro-surgical instrument for removing human tissue, comprising a hollow stem of insulating material open at one end and adapted to be connected to a vacuum device for creating a suction at said open end to draw in and hold said tissue, an electrode in said stem having a portion thereof disposed adjacent said open end so as to intimately contact said drawn-in tissue, means for connecting said electrode to a source of current supply, and means for limiting the amount of tissue to be suctionally drawn into said open end, said last named means comprising a sleeve mounted on said stem adjacent the open

end thereof, said sleeve being movable axially to project beyond the said open end of said stem to form a suction cup area, said projecting portion of said sleeve terminating in a constricted opening to cause said drawn-in tissue to assume a shape having an enlarged outermost portion adjacent to a constricted portion.

5. An electro-surgical instrument for removing human tissue, comprising a hollow stem of insulating material open at one end and adapted to be connected to a vacuum device for creating a suction at said open end to draw in and hold said tissue, said open end being adapted to be stoppered by said drawn-in tissue, an electrode in said stem having a portion thereof disposed adjacent said open end so as to intimately contact said drawn-in tissue, means for connecting said electrode to a source of current supply, and means for preventing the energization of said electrode without first rendering said vacuum device effective for drawing in said tissue, said last named means comprising an insulated handle member attached to said stem, said handle member having an air passageway connected to said vacuum device and communicating with the interior of said hollow stem, and a valve member normally interrupting the passage of air through said passageway.

6. An electro-surgical instrument for removing human tissue, comprising a hollow stem of insulating material open at one end and adapted to be connected to a vacuum device for creating a suction at said open end to draw in and hold said tissue, said open end being adapted to be stoppered by said drawn-in tissue, an electrode in said stem having a portion thereof disposed adjacent said open end so as to intimately contact said drawn-in tissue, means for connecting said electrode to a source of current supply, and means for preventing the energization of said electrode without first rendering said vacuum device effective for drawing in said tissue, said last named means comprising an insulated handle member attached to said stem, said handle member having an air passageway connected to said vacuum device and communicating with the interior of said hollow stem, and a valve member normally interrupting the passage of air through said passageway, said valve member being so disposed that the effective operation of said suction device will cause it to be moved to open position.

7. An electro-surgical instrument for removing human tissue, comprising a hollow stem of insulating material open at one end and adapted to be connected to a vacuum device for creating a suction at said open end to draw in and hold said tissue, said open end being adapted to be stoppered by said drawn-in tissue, an electrode in said stem having a portion thereof disposed adjacent said open end so as to intimately contact said drawn-in tissue, means for connecting said electrode to a source of current supply, means for preventing the energization of said electrode without first rendering said vacuum device effective for drawing in said tissue, said last named means comprising an insulated handle member attached to said stem, said handle member having an air passageway connected to said vacuum device and communicating with the interior of said hollow stem, a valve member normally interrupting the passage of air through said passageway, said valve being so disposed that the effective operation of said suction device will cause it to be moved to open position, and means for completing an elec-

tric circuit between said electrode and said source of current supply upon such movement of said valve.

8. An electro-surgical instrument for removing human tissue, comprising a hollow stem of insulating material open at one end and adapted to be connected to a vacuum device for creating a suction at said open end and to draw in and hold said tissue, said open end being adapted to be stoppered by said drawn-in tissue, an electrode in said stem having a portion thereof disposed adjacent said open end so as to intimately contact said drawn-in tissue, means for connecting said electrode to a source of current supply, means for preventing the energization of said electrode without first rendering said vacuum device effective for drawing in said tissue, said last named means comprising an insulated handle member attached to said stem, said handle member having an air passageway connected to said vacuum device and communicating with the interior of said hollow stem, a valve member normally interrupting the passage of air through said passageway, said valve being so disposed that the effective operation of said suction device will cause it to be moved to 25

open position, and means for completing an electric circuit between said electrode and said source of current supply upon such movement of said valve, said hollow stem material being manually bendable whereby to cause the same to assume a shape designed to facilitate access to otherwise inaccessible tissue parts.

9. An electro-surgical instrument for removing human tissue by coagulation, comprising a hollow stem of insulating material open at one end and adapted to be connected to a vacuum device for creating a suction at said open end to draw in and hold said tissue, an electrode in said stem having a tip member so disposed with respect to said open end that the said suctionally drawn-in tissue will be brought into intimate contact with said tip member, said tip member being axially movable with respect to said electrode, and means for connecting said electrode to a source of current supply, said hollow stem material being manually bendable whereby to cause the same to assume a shape designed to facilitate access to otherwise inaccessible tissue parts.

WILLIAM BIERMAN.
